LOCOMOTIVE STOKER

Charles J. Surdy, Tuckahoe, N. Y., assignor, by
mesne assignments, to The Standard Stoker
Company, Inc., New York, N. Y., a corporation
of Delaware

Application November 15, 1934, Serial No. 753,090

3 Claims. (Cl. 198—15)

My invention relates to locomotive stokers of the class comprising a plurality of fuel conveyors arranged with two of the conveyors offset laterally from each other at their adjacent ends and having independent drive connections at their rearward ends.

It is the principal object of the invention to improve upon stokers of the aforesaid class by substantially reducing the angular relation between the conveyors. More specifically, I contemplate the provision of a stoker having a fuel receiving conveyor on the tender, a fuel delivery conveyor on the locomotive, and an intermediate conveyor, the latter being offset laterally at one end from an adjacent end of one of the other conveyors and said adjacent end of that conveyor disposed at one side of the vertical medial plane of the locomotive and tender or at one side of the vertical medial plane of the other of said conveyors.

Another object is the provision of a specific embodiment of the invention as above wherein the rearward end of the intermediate conveyor is offset laterally from the forward end of the tender conveyor.

A further object of the invention is the provision of stokers of the class described wherein the tender conveyor is disposed with the axis thereof lying at one side of and substantially parallel to the vertical medial plane of the tender or wherein said axis extends diagonally of and passes through said plane.

A still further object of this invention is the provision of a stoker of the character specified which is suitable for use in connection with locomotives and tenders of conventional design.

Other objects and advantages of the invention will be apparent as the following description is read in connection with the accompanying drawings, in which,

Figure 1 is a medial vertical section of adjacent parts of a locomotive and tender, showing the invention in position thereon with portions broken away;

Figure 2 is a plan sectional view taken on the line 2—2 of Figure 1, with portions of the locomotive and tender indicated by conventional lines;

Figures 3 and 4 are sectional views taken on lines 3—3 and 4—4, respectively, of Figure 1;

Figure 5 is a sectional view taken on the line 5—5 of Figure 2;

Figure 6 is a view similar to Figure 2, illustrating another embodiment of my invention; and

Figure 7 is a sectional view taken on the line 7—7 of Figure 6.

In Figures 1 to 5, inclusive, illustrating an embodiment of my invention, A represents the locomotive, B its tender, and C the coupling member therebetween, permitting articulation when the locomotive and tender are rounding curves or passing over switches and turntables. The locomotive A comprises a boiler 10 having a backwall 11 in which there is the usual firing opening 12, establishing communication between the cab 13 and the firebox 14. Above the floor 15 of the tender B is a fuel bin 16, the floor 15 being apertured centrally of the fuel bin as at 17, the size of which aperture is controlled by the 15 slidable plates 18.

Extending from beneath the apertured floor of the tender to the firebox of the locomotive is a stoker, indicated generally at S. The stoker S comprises the fuel receiving or tender conveyor D, the delivery conveyor E, and the intermediate conveyor F. The delivery conveyor E includes an inclined conduit 19 mounted on the locomotive and communicating with the firebox 14 through the opening 12, and an elevating or fuel delivery conveyor screw 20 housed within the conduit 19 for delivering fuel to a distributing means 21 which spreads the fuel to all parts of the firebed. The elevating screw 20 and the conduit 19 are mounted so that their respective axes are in substantially the vertical medial plane of the locomotive and tender, or so that the fuel delivery mouth of the conduit 19 is disposed substantially equally on each side of such plane.

The tender conveyor D is rigidly mounted beneath the apertured floor 15 of the tender in the compartment 22 and includes a trough-like conduit 23 provided with an open mouth 24 through which fuel falls from the bin 16 into the trough 23. The open mouth of the trough 23 is at least 40 equal to the width and length of the aperture in the floor 15 to prevent loss of fuel. Fuel which is received within the trough-like conduit 23 is conveyed forwardly by conveyor screw 25 disposed within the trough with its axis at one side 45 of and parallel to the vertical medial plane of the locomotive and tender. The screw 25 extends the length of the open mouth trough 23 and into a tubular extension 26, rigid with the trough and coaxial with the conveyor screw 25. A spherical 50 member 27 is formed externally of the tubular extension and at the forward end thereof.

The fuel receiving conveyor screw 25 delivers fuel to the screw 28 of the intermediate conveyor F, which screw has the forward end 29 thereof 55
